[57] **CLAIM**

The ornamental design for a handle support for weed cutting implements, as shown and described.

DESCRIPTION

FIG. 1 is a perspective view of a handle support for weed cutting implements showing my new design;

FIG. 2 is a fragmentary side elevation thereof;

FIG. 3 is an end elevation thereof;

FIG. 4 is a fragmentary side elevation of a modified embodiment of the handle support illustrated in FIG. 2;

FIG. 5 is an elevation as seen from the right of FIG. 4;

FIG. 6 is a fragmentary side elevation of still a further modified embodiment of the handle support illustrated in FIG. 2; and

FIG. 7 is an elevation as seen from the right of FIG. 6.

FIG. 1

FIG. 2

FIG. 3

FIG. 4

FIG. 5

FIG. 7

FIG. 6
